DESIGN FOR A MATCHBOX HOLDER

Fred H. Lewis, Evanston, Ill.

Application May 19, 1945, Serial No. 119,626

Term of patent 14 years

(Cl. D48—28)

To all whom it may concern:

Be it known that I, Fred H. Lewis, a citizen of the United States, residing at Evanston, in the county of Cook and State of Illinois, have invented a new, original, and ornamental Design for Matchbox Holder, of which the following is a specification, reference being had to the accompanying drawing, forming part thereof.

In the drawing, Figure 1 is a perspective view of a matchbox holder, showing my new design, and Figure 2 is a side elevational view of the same.

I claim:

The ornamental design for a matchbox holder, substantially as shown.

FRED H. LEWIS.
